UNITED STATES PATENT OFFICE.

WALTER SCOTT, OF CHICAGO, ILLINOIS.

MOLD FOR CASTING STEREOTYPE-PLATES.

SPECIFICATION forming part of Letters Patent No. 243,981, dated July 5, 1881.

Application filed June 18, 1879.

To all whom it may concern:

Be it known that I, WALTER SCOTT, of Chicago, in the county of Cook and State of Illinois, have invented certain new and useful 5 Improvements in Molds for Casting Stereotype-Plates, which are fully described in the following specification, reference being had to the accompanying drawings, in which—

Figure 1 represents a plan view of a mold 10 embodying my improvements in position to receive the matrix or to remove the plate after casting; Fig. 2, an end elevation of the same, looking toward the bottom end of the mold, and with the cope thrown up; Fig. 3, a trans- 15 verse section of the same, taken on the line $y-y$, Fig. 1; Fig. 4, a longitudinal section of the same, taken in the line $x-x$, Fig. 1; Fig. 5, a side elevation of the same, the mold being tilted in position for turning the molten metal; 20 Fig. 6, a bottom plan of the cope; Fig. 7, a detail section taken on the line $z-z$, Fig. 2; and Fig. 8 a plan of one of the side bars.

My invention relates to a mold for casting curved stereotype-plates for use upon cylinder-presses.

The invention consists in special mechanisms and combinations of devices, which will be hereinafter fully described, and will be pointed out definitely in the claims.

30 In the drawings, A represents a supporting-frame, which in this instance has triangular end pieces, in the upper ends of which the drag B of the mold is mounted by means of trunnions b near the middle of the drag, which 35 are supported in suitable bearings a on the end pieces. The drag is concave, the curvature corresponding to that desired in the stereotype-plate.

The cope C is made, as usual, so as to fit into 40 the drag B, and is provided upon its convex surface with transverse grooves c for forming the usual ribs on the concave surface of the stereotype-plate. On one side of the cope are lugs D, projecting laterally from the upper 45 edge of the cope. These lugs are hinged or pivoted to suitable lugs, D', projecting from one side of the drag, near the upper edge thereof, so that the cope is thereby attached by a hinge-joint to the drag, the hinges being arranged 50 at one side of the mold, which permits the cope to be raised from the drag and turned outward to one side thereof.

Weights E are either cast with or attached to the lugs D, being arranged on arms which extend beyond the pivot of the hinges, as shown 55 in Fig. 1 of the drawings. These weights counterbalance the weight of the cope, so that the latter is easily raised and turned outward on its hinges. On the opposite side of the cope are lugs F, which have one portion, a smooth 60 face, f, slightly raised above the edge of the cope, and another portion, f', projecting still farther upward and outward, which furnish bearings for a shaft, G, on which are arranged cams g. The shaft is also provided with a 65 handle, g'.

Clamps H are pivoted to the side of the drag, and are arranged so as to be turned up over the faces f when the cope is lowered into the drag, and are provided at their upper ends 70 with clamp-screws h, which are turned down upon the faces f to fix the cope in position and hold it firmly there.

At the lower or inner end of the drag is a bar, I, which is curved to fit the concavity of 75 the drag, and is provided on its outer edge with notches i, arranged to engage with pins i' on the drag, by means of which it is held in place, while at the same time it may be vibrated and removed whenever desired, and to 80 facilitate its removal or vibration is provided at one end with a handle, i², projecting outside beyond the side of the drag. The inner edge of this bar is beveled to correspond to the bevel which is desired on the end of the 85 stereotype-plate. There are also notches or recesses i³ cut in this inner edge of the bar at or near the edges of the drag. There are also provided side bars, K, the inner ends of which are stepped so as to make a projection, k, 90 adapted to enter the recess i³ in the edge of the bar I. These side bars are beveled at their inner edges, and are cut away slightly on the inside of said edges to form a rabbet, k', so that when the bars are in place there will be 95 a narrow vacant space between the lower edges of the bars and the concave face of the drag, as shown in Fig. 3 of the drawings. These bars are also provided with pins k² near their outer ends, which enter holes in the drag pro- 100 vided to receive them, by means of which the bars are secured in position. The bars are also provided with handles k³ at their outer ends, by means of which they are readily de-

tached from the drag or placed therein, as occasion requires.

At the upper end of the drag there is also a curved plate, L, adapted to fit the drag, and extending into the latter beyond the end of the cope when closed. The object and use of this plate are known and do not require particular description here.

A spring-lever, M, is attached to the supporting-frame and provided near its upper end with a stud, m, which is arranged to enter a series of holes, m', in one of the trunnions of the drag, whereby the latter is locked in either a horizontal position, as shown in Fig. 4 of the drawings, or a nearly vertical position, as shown in Fig. 5.

In operation this mold is used in the usual way. The matrix being placed in position and the cope closed down into the drag, the mold is turned into the position shown in Fig. 5 of the drawings, when the type metal is poured into the mold at the upper end. When the metal is cooled in the mold the latter is turned back again into the horizontal position, as shown in Figs. 1 and 4 of the drawings, and the cope is released and swung upward and outward to one side, as shown in Fig. 2 of the drawings. The side bars are removed and the plate started by turning the curved end bar I inward, the upper pins on the drag serving as pivots for this purpose. The cast plate may then be readily removed from the drag.

It is evident that the rabbets on the edges of the side bars will permit the edges of the matrix to enter the space underneath the edges of the side bars. This holds the matrix in place and prevents it from slipping.

As stated above, the mold is fastened in its

upright or horizontal position by means of the spring-lever M. The cope is started from its 40 position in contact with the type-metal by turning the lever g', whereby the cams g, acting upon the edge of the drag, will lift the cope slightly from the metal, overcoming all sticking, so that the cope may be then turned outward with ease. The hinging of the cope so as to swing it outward at one side of the drag 45 obviates all necessity of any special form of groove or hinge, for the movement of the cope is in direct line with the grooves in its convex 50 surface, and therefore when started away from the plate there will be no danger of injuring the ribs on the latter.

Having thus described my invention, what I claim as new, and desire to secure by Letters 55 Patent, is—

1. The pivoted drag B, in combination with the cope C, having transverse grooves on its convex surface and hinged at one side to the drag, whereby when the cope is swung outward the grooves are lifted in straight lines from the metal which they inclose, thus preventing pinching, substantially as described. 60

2. The drag B, in combination with the cope C, hinged to one side of the former, and the 65 counterbalancing-weights E, attached to the cope and extending outside of the hinged pivots, substantially as described.

3. The spring-lever M, provided with stud m, in combination with the pivoted drag B, 70 provided with a series of holes, m', in one of its trunnions, substantially as described.

WALTER SCOTT.
